(57) **CLAIM**

The ornamental design for an electrode patch array, as shown and described.

DESCRIPTION

FIG. 1 is a bottom perspective view of an electrode patch array showing my new design;

FIG. 2 is a top perspective view of the electrode patch array;

FIG. 3 is a bottom view of the electrode patch array;

FIG. 4 is a top view of the electrode patch array;

FIG. 5 is a left side view of the electrode patch array;

FIG. 6 is a right side view of the electrode patch array;

FIG. 7 is a front view of the electrode patch array;

FIG. 8 is a rear view of the electrode patch array; and,

FIG. 9 is an exploded perspective view of the electrode patch array.

The broken lines in the drawings depict portions of the electrode patch array that form no part of the claimed design.
